(345 W. 6th St., Garnett, Kans. 66032)

Filed June 10, 1968, Ser. No. 12,274

Term of patent 14 years

Int. Cl. D26—02, 04

U.S. Cl. D48—4

FIG. 1 is a side elevational view of my trouble light support embodying my new design;

FIG. 2 is a front elevational view of same; and

FIG. 3 is a top plan view of same.

The trouble light is shown in broken lines in FIG. 1 for illustrative purposes only. The support is broken away in FIGS. 1 and 2 to indicate indeterminate length.

I claim:

The ornamental design for a trouble light support, as shown and described.
